CONTAINER VALVE

Stephen D. Hartog, Normandy Township, St. Louis County, Mo.

Application March 5, 1937, Serial No. 129,147

10 Claims.

(Cl. 221—60)

This specification, aided by the accompanying drawing, discloses certain improvements in container valves.

In that special branch of commercial production and distribution certain containers, collapsible tubes and the like are employed to vend plastic materials such as tooth-paste, vaseline, and various other materials including medicinals having a paste-like consistency, and the practical means employed to discharge a requisite quantity of the contents of the container tube is by means of squeezing a portion of the container tube to a compressed condition, thereby dispensing the needed quantity through the aperture provided within the projecting neck formed on the container tube. The discharge aperture, of the container tubes most numerous in use, is opened and closed by means of a screw-threaded cap removably attached to the screw-threaded surface formed upon the apertured neck. The screw-threaded type of removable caps has many objectionable characteristics, not only because of the possibility of the cap being dropped upon the floor while being unscrewed thereby encountering a possible loss of the cap, but also because of the fact that the screw-threading of the cap and the tube is an appreciably expensive process to be expended on an article discarded as so much scrap material when its contents have been consumed.

The container valve herein described and illustrated is primarily directed to overcome, not only the objectionable characteristics of the screw-threaded type of construction, but also to provide a container valve appreciably more economical to manufacture and as an article of manufacture constituting a complete assembly unit.

Briefly summarized, the herein described and illustrated improvements provide:

A container valve simple in construction and operation.

A container valve having few parts and therefore of minimum production cost.

A container valve designed and constructed for production by means of a die-forming process.

A container valve openable by manually drawing the cap in one direction and then swinging the cap laterally to expose the discharge aperture.

A container valve capable of being securely locked in a closed position.

A container valve non-leakable.

A container valve that will resist leakage under pressure.

For the purpose more clearly to understand the expressed objects and other attending objects of

this improved container valve, the following description is given, and by aid of the accompanying drawing, it is discernible:

Fig. 1 is a view in elevation of the container valve in mounted position on a fragmentary portion of a collapsible tube. 5

Fig. 2 is a view of the container valve in cross-section, line A—A, Fig. 1.

Fig. 3 is a plan view of the cap.

Fig. 4 is a side view of the cap. 10

Fig. 5 is a plan view of a strip of metal bent angularly.

Fig. 6 is a side view of the metal strip.

Fig. 7 is an end view of the strip.

Fig. 8 is a plan view of a metal shell or container neck fitting body. 15

Fig. 9 is a side view of the shell or body.

Fig. 10 is a dotted outline of operational features of the container valve.

The features constituting this improved container valve construction are herein designated numerically, and in the order of which 10 designates a fragmentary portion of a container, denominated a collapsible tube. 20

Formed on the tube 10 is an apertured projecting neck 11. Into the apertured projecting neck 11 a tubular shell 12 is secured as and when prepared in accordance with the description herein-after more fully explained. 25

The container valve herein described and illustrated constitutes a construction of valve produced by means of a "die-forming process"; consequently, its production cost is reduced to a minimum. 30

In this specification the expression "shell-formed tubular body", and "container neck fitting body" are to be regarded as equivalent expressions relating to a particular member part of this construction. This improved container valve comprises an assembly of member parts in which there is employed a shell-formed tubular body 12 provided with a flanged end 13 terminating in a rim 14 having depending portions 15 and 16. The depending portions 15 and 16 are formed and positioned diametrically opposite each other on the tubular body 12. The depending portions 15 and 16 extend axially lengthwise of the tubular body 12 and are dimensioned measureably short of its entire length. Formed within the depending portions 15 and 16 are openings providing slots 17 and 18 which slots resemble in form and appearance an inverted T, the form of which extends axially lengthwise thereof in one direction 40 on the depending portion of the tubular body and 45

radial in the other direction for a limited distance circumferentially therearound.

A disc shaped cap 19 is also a member part of this construction and has provided upon one of its faces a projecting portion 20 dimensioned to fit snugly into the tubular body at the designated open end thereof 21. Upon a face opposite to that of the projecting portion 20 is an elevation 22 and within which elevation a counter-sunk channel 23 is provided. Adjacent the channel 23 and in alignment therewith apertures 24 and 25 are provided marginally spaced within the larger diameter of the disc cap 19, and the circumferential contour of the enlarged diameter at 26 is knurled to accommodate manipulation.

Included in this construction of container valve is an angularly formed metal strip 27 having a straight flat portion 28 with angularly bent portions 29 and 30 providing depending prongs. Marginally spaced from the extreme end of the prongs 29 and 30 are cut-out forms providing notches 31 and 32 leaving a narrow stay portion of metal 33 and 34 the marginal ends 35 and 36 of which are semi-circular in form. The angularly formed metal strip 27 thus formed is arranged in assembly with the disc cap 19. The metal strip is then assembled upon the cap 19 with prong portions 29 and 30 entered into the apertures 24 and 25 and pressed to a position in which the flat straight portion 28 of the metal strip 27 rests seatedly within the channel 23. This arrangement suggests firstly; the bending of the stay portions 33 and 34 in a rectangular form in parallel relation with the straight flat surface portion 28. The cap assembly is then positioned on the shell-formed tubular body 12. The rectangularly bent stay portions 33 and 34 are sprung over the depending portions 15 and 16 and entered into the arcuately radial openings of the inverted T-formed slots 17 and 18. The cap assembly is then swung to a position to permit the insertion of the projecting portion 20 to be entered into the tubular opening 21, and while in this assembled condition the stay portions 33 and 34 are again bent in an axially lengthwise direction with respect to the longitudinal axis of the tubular body 12, thus providing a complete assembly unit container cap.

The unit thus formed is then attached to a container or collapsible tube 10, and this is accomplished by pressing the tubular body 12 into the aperture provided within the neck 11 of the container, including collapsible tubes. The tubular body 12 is dimensioned measurably greater in length than the length of the neck 11 of the tube, and this excess length of the tubular body is then spun over, by means of a spinning tool, thereby forming a turned over flanged end 39 whereby the entire valve assembly unit is fixed securely to the container or collapsible tube.

The container valve thus arranged is operable manually by drawing the cap upwardly from off its seat to a position approximately to that indicated in dotted outline Fig. 1; the cap is then swung latterly (indicated in dotted outline Fig. 1) within the radius "R" so that the discharge aperture 21 of the container is completely uncovered and free to discharge the contents unobstructedly. It is obvious that the closing of the discharge aperture is only the reverse of the opening process.

The successful operation of this container valve is the result of its novel features of construction combined with the co-operative functioning of its several parts. The form of the openings provid-

ing the slots 17 and 18 within the depending portions 15 and 16 forms that which may be defined as a guide-way for the engaging bent ends of the prongs 33 and 34. Provision is also made by means of which the cap 19 can be locked securely while in a closed position on the container. The bent notched ends of the prongs have slideable bearings within the axially lengthwise slots 17 and 18. The slots 17, 18 also provide at their extreme end a bearing within which the bent over ends of the prongs have pivots provided by the narrow stay portions 33 and 34 of the notched ends 31 and 32 of the prongs. The bent over ends 35, 36 are semi-circular in form and their end surfaces provide a stop limiting the upward slideable movement of the cap at the instance of their contacting with the under surface 13 of the flanged end of the tubular body 12.

Referring to Fig. 10 of the drawing, operational features of the end bearings of the depending prongs are outlined. Observing that when the cap is elevated to a position indicated in dotted outline Fig. 1, the stay portions 33 and 34 are in a position to pivot in the guide-way slot 17 (the pivotable position of the prongs 29, 30 being indicated in dotted outline), and in which position the cap 19 would be moved within the sweep of the dotted outline radius "R" Fig. 1. At the instant the cap is closed or seated, with the projection thereof 20 within the aperture 21, the cap is susceptible of being swerved or turned arcuately in a right hand or left hand direction about 5 and 10 degrees, the result of such movement is to bring the stay bearing portions 33 and 34 into the arcuately radial openings of the apertured slots 17 and 18 thus providing a lock for the cap when closed. The position of the depending prongs 29, 30 is indicated in dotted outline to the right and left of the apertured opening 17, showing the position of the prongs when in locked engagement. The turned over portions 15 and 16 have bearing surfaces provided at the extreme ends 37 and 38, which ends contact with the exterior surface of the tube 10, adjacent the neck 11.

Owing to the design and construction of the shell-formed tubular body 12, a neck portion is thus formed having a portion which may be of any suitable length. The apertured neck 11 of the tube can be made very short because the shell-formed tubular body 12 is formed in such a way that the turned over portions 15 and 16 at 37 and 38 bear upon the external surface of the container adjacent the apertured neck 11 so that when the end 39 of the tubular body is flanged over the tubular shell body 12 thus becomes a neck-forming body in and of itself.

Resulting from the description thus given, it is obvious that there is provided a container valve of the character described, and possessed of the advantageous features hereinbefore enumerated as desirable. It is therefore to be understood that the container valve is susceptible of modification in its form, proportions, detailed construction and arrangement of parts without departing from the principle involved or sacrificing any of its advantages.

The invention has been described in language more or less specific as to structural features; it is to be understood that the invention is not limited to the specific details shown, but that the means and construction herein disclosed comprise the preferred form of several modes of putting the invention into effect and the invention therefore is claimed in any of its forms or modifica-

tions within the legitimate and valid scope of the appended claims.

I claim, and desire to secure by Letters Patent of the United States of America, this invention as, in, and for:

1. A container valve comprising an apertured shell-formed tubular body having a rim, a flanged end on the tubular body, the said rim and the said flanged end of the tubular body providing the means by which the shell-formed tubular body is attachably secured to a container, and a closure cap for the aperture within the shell-formed tubular body.

2. A container valve comprising an apertured tubularly formed body having an end portion turned over providing a flange terminating in a rim, an enlargement upon the tubularly formed body having engaging contact with the surface of the container adjacent the aperture within which the tubularly formed body is positioned, the end portion of the tubularly formed body within the said aperture having a turned over portion flanged to attachably secure the said tubularly formed body to a container, and a closure cap to close the aperture within the tubularly formed valve body.

3. A container valve comprising an apertured shell-formed tubular body having a rim, a flanged end on the tubular body, the said rim and the said flanged end, one with the other, providing the sole means by which the said shell-formed tubular body is attachably secured to a container, and a closure cap adapted for pivotal movement upon the said tubular body and to close the aperture therein.

4. A container provided with a valve comprising a contiguous metal body having an apertured tubular portion and an over-lapping concentric portion in spaced relation with the tubular portion, axially lengthwise and arcuately formed slots within the over-lapping concentric portion, the end face surface of the said over-lapping portion having contact engagement with the surface adjacent the aperture of the said container, a flanged over end portion formed on the said tubular portion, the said end face surface and the said flanged over end portion providing the means by which the said container valve is adapted to be attached to a container, and a closure cap adapted for slidable and pivotal movement on the said concentric portion of the metal body, and means on the closure cap engaging with means formed on the said concentric portion, whereby the closure cap is connected operatively for slidable and pivotal movement upon the said contiguous metal body.

5. A container valve of the class described com-

prising in combination, a collapsible tube having a discharge end aperture, a valve having a shell-formed tubular body, a concentrically enlarged portion formed on the said tubular body providing a rim, a flanged end portion formed on the said tubular body, the said rim and the said flanged end portion providing the means by which the said valve unit assembly is securely connected within the aperture of the said collapsible tube, a closure cap adapted for pivotable movement upon the said shell-formed tubular body, and locking means for the said cap.

6. A valve of the class described comprising in combination an apertured collapsible tube, a valve body having a flanged end terminating in a rim, an end portion adapted to fit the discharge end of the said tube, the said end portion formed to secure the valve body to the collapsible tube, and a closure cap adapted for slidable and pivotal movement on the said valve body.

7. An apertured neck portion adapted to be attached to a container the said neck portion comprising a tubular body having a turned over portion providing a rim, means in the rim providing engaging connection for a slidable cap having pivotal movement within the said rim portion of the container neck, and locking means for the said cap, and means to secure the said neck to the container.

8. A container valve body adapted to be attached to the neck of a container, the container valve body comprising a tubular formed body, a turned over portion formed on the tubular body, the turned over portion adapted to contact upon the surface of the container adjacent the discharge end, the tubular body having the marginal end thereof flanged over whereby the attachable container valve body is securely connected to a container.

9. As a new article of manufacture, a collapsible tube valve body comprising a tubularly formed body having a concentrically enlarged portion formed on the tubular body providing a rim, an end portion of the tubular body adapted to fit the discharge aperture within the collapsible tube and an end portion crimped to secure the valve body to the collapsible tube.

10. As a new article of manufacture, a valve body adapted for use on a collapsible tube, the said article of manufacture comprising a tubularly formed contiguous body having an end portion thereof terminating in deflected portions concentric with the said tubular body, slots within the said deflected portions, and a marginal end of the said tubular body formed to secure the said valve body to the collapsible tube.

STEPHEN D. HARTOG.
